Inventor:

James D. Gibbs

UNITED STATES PATENT OFFICE.

JAMES D. GIBBS, OF LOUISVILLE, KENTUCKY, ASSIGNOR TO GIBBS-INMAN COMPANY,
OF LOUISVILLE, KENTUCKY.

RAILWAY-TICKET.

1,129,662.

Specification of Letters Patent. Patented Feb. 23, 1915.

Application filed January 2, 1914. Serial No. 809,814.

To all whom it may concern:

Be it known that I, JAMES D. GIBBS, a citizen of the United States, residing at Louisville, in the county of Jefferson and State of Kentucky, have invented new and useful Improvements in Railway-Tickets, of which the following is a specification.

My invention relates to the class of railway passage tickets known as local or station tickets, and has for its object the increasing of the efficiency of each ticket and a consequent reduction in the railway company's investment in tickets. Heretofore all tickets of this class have been arranged to comprise two specific portions, a passage portion to be delivered to the passenger, and a stub portion to be retained by the agent as his record.

In my ticket I employ a double column of destination stations, so imposed upon the ticket, that the ticket seller can, with facility, designate a station in either column, whereby either part, as predetermined, unalterably becomes the passage ticket and the part detached therefrom the agent's record portion.

In the accompanying drawings,—Figure 1 is a view of my ticket, severed or executed for a given destination and class in one of the columns, whereby the part of the ticket bearing said indicated destination and class becomes the passage portion and the other part the agent's stub. Fig. 2 is the same ticket, having indicated a destination and class in the opposite column, thereby causing the passage portion and stub portion to be the reverse of those shown in Fig. 1. Figs. 3 and 4 are modified forms of my ticket designed to have the destination and class indicated with a shorter or smaller notch if it be deemed desirable, or to utilize a cutter now in common use, forming on the ticket a double point, as at *i*. Fig. 5 is a view of the cutter, showing its general form, but it is understood that the points of the cutter are made to conform to the specific arrangement of the tickets in connection with which they are to be used.

In Figs. 1, 2, 3 and 4, A is the passage portion and B the stub portion; *a a*, are the destination stations; *b b* are the record stations and *c c* the class indicia. All other printing on the ticket is of the customary form except that instead of designating one

part of the ticket as an agent's stub, both halves of it are printed identically, numbered in duplicate in the spaces *d d*, and adapted to utilize either half of the ticket as the passage portion, the unused portion 60 automatically becoming the agent's stub or record portion.

In Fig. 5, C is the base block, D is the straight edge, having the fixed points *e e*; *f* is the retaining strip for the sliding point 65 *g*. The straight-edge is normally held a short distance above the block by small springs at each end while *h h h h* are screws anchoring straight-edge to the block.

In practice, the ticket is placed under the 70 straight-edge so that the proper class designation comes directly opposite and adjacent to one of the fixed points of the cutter and the column of stations in which the destination is located is in full sight; the cutter 75 is then pressed down upon the ticket and the sliding point is moved up or down the straight-edge until it registers exactly with the elected destination, when, with a brisk movement, the free end of the ticket is 80 raised until the points have cut through it, and the separation of the passage portion from the stub or agent's portion is completed by tearing the ticket along the straight-edge. In case the desired destination 85 should be found in the other column of stations, the operator will reverse or invert the ticket and place the opposite side of it under the cutter. The portion having the notches is the passage portion, while 90 that bearing the tongues or projections is the stub portion.

If the ticket is sold under conditions requiring no class designation, it is placed under the cutter between the two fixed points 95 thereof and the sliding point is used to indicate the destination.

It is well known that the tongue or projections on the stubs of all tickets of this class are liable to mutilation, not infrequently wholly or partially obliterating the station name on the end of the tongue, leaving the auditor in doubt as to the exact destination for which the ticket was sold. To overcome this I preferably show on the 100 tongue of the agent's stub at least one station printed on either side of the destination station as it appears in Fig. 1, thereby enabling the auditor, in case the tip of the projection is defaced, to determine the des- 105 110

tination by comparing the stub with any other ticket of the same form. Or, if deemed desirable I claim the right, without departing from the spirit of my invention, 5 to remove all the secondary stations a sufficient distance from the end of the projection to cause them all to appear on the detached stub, as shown in Figs. 3 and 4.

It will be seen that in my ticket the number of destination points is doubled, thus necessitating only half the number of forms required under present system to embrace all the stations on a given line or railway, which, in a large railway, is a serious consideration. The investment in the local 15 tickets is curtailed fifty per cent., and the storage or case-room in both the general office and station, as well as the labor of accounting are proportionately diminished.

20 Having described my invention, what I now claim is:

1. A railway ticket having margin portions printed with ticket matter in duplicate, and between said margin portions two 25 principal rows or columns of different station names, and having opposite each name of each column a repeat of said name, said ticket being adapted to be separated between said columns into two parts whereby either 30 part may serve as a passage portion or agent's stub.

2. A railway ticket having printed there-

on in reverse order two principal rows or columns of different station names and having opposite each name of each column a 35 repeat of said name, said ticket being adapted to be separated between said columns into two parts, and each part bearing ticket data whereby either one may serve as a passage portion or agent's stub.

3. A railway ticket having printed thereon two principal rows or columns of different station names and between said columns two rows of repeats of the names of the 45 principal columns, said ticket being adapted to be separated between said columns into two parts and each of said parts having ticket data whereby each of said parts is adapted to serve as a passage portion or agent's stub.

4. A railway ticket having printed thereon in reverse order and staggered relation two rows or columns of different station names and having opposite each name of each column a repeat of said name, said 55 ticket being adapted to be separated between said columns into two parts and each of said parts bearing ticket data whereby either part may serve as a passage portion or agent's stub.
